APPARATUS FOR PRODUCTION OF UNIFORM SPECIMEN COATINGS

Kurt R. Fisch and Henry Gisser, Philadelphia, Pa., assignors to the United States of America as represented by the Secretary of the Army

Application November 30, 1955, Serial No. 550,226

1 Claim. (Cl. 118—404)

(Granted under Title 35, U. S. Code (1952), sec. 266)

The invention described herein may be manufactured and used by or for the Government for governmental purposes without the payment of any royalty thereon.

Our invention relates to evaluation of the protective properties of semi-fluid substances. More particularly, the invention is directed to apparatus for attainment of uniform coating of specimen surfaces with grease-like substances whose performances in the role of corrosion prevention are desired to be measured.

Reliability of results in the envisaged measurements is dependent basically upon the ability to repeatedly produce a uniform coating or test film of the substance under investigation. That is to say: that the thickness of the applied film should closely approach uniformity over an entire test surface; that the film thickness of a given substance applied to several standard test-surface specimens should be substantially the same; and the thickness of film of various related substances under comparison, applied to corresponding sets of standard test-surface specimens, should be substantially the same.

The work which led to the apparatus of the present invention dealt in particular with appraisal of the rust-preventive value of greases.

Various devices for producing specimen films of controlled thickness have evolved in the protective and decorative coating industry, in response to a need of spreading for evaluation paint and varnish in uniform thicknesses over flat test surfaces. Those devices include single and double-action spinners, manual and automatic doctor blades, dip coaters and others, as described in "Physical and Chemical Examination, Paints, Varnishes, Lacquers, Colors" by Gardner and Sward, 10th edition, Chapter 9.

Devices of the cited kind were found unsatisfactory for determination of the rust-preventive properties of grease-like substances. The reasons were seen to be: unproductivity, within practical limits, of flat surfaces in themselves of sufficient uniformity to base a coating of a degree of evenness essential to valid results and pronounced "edge" effect at the extensive perimeter of flat test-surface specimens, which effect is a creeping of moisture under the coating at the edges whereby results are vitiated.

It was visualized that cylindrical test-surface specimens at once would facilitate attainment of required uniformity of surface and minimize "edge" effect. Consequently we set as our object a provision of apparatus adaptive of cylindrical specimens and requiring but ordinary manipulative skill in use.

We now have accomplished that object by providing a combination of: means for manipulatively holding a cylindrical, test-surface specimen; means cooperating with the holding means to reciprocatively guide the latter; and means associated with the guiding means for housing and confining a grease-like substance under pressure cooperatively with the specimen; so that upon completion of a reciprocatory cycle of the holding means, a film of desired character of the grease-like substance is caused to be deposited upon the specimen.

2

The specific structures of an embodiment whose effectiveness in use has been established are illustrated in the accompanying drawings wherein:

5 Figure 1 depicts, sectionally in part, the several elements of the structures in their relationship when housing a test substance preparatory to use.

10 Figure 2 reflects similarly the relationship of components when confining a grease-like substance under pressure and the holding structure has been manipulated to the limit of its stroke inwardly of its guiding structure.

15 Figure 3 shows the relationship when the holding structure has been retracted, and partially disengaged of its guide.

Figure 4 represents the holding structure separate from the other structures of the embodiment.

Reverting to Figure 1, the numeral 1 designates a cylindrical test-surface specimen. 2 is a piston-like holder of the specimen, having a central bore 3 in which one end of the specimen is concentrically seated. 4 is a bore vent to facilitate seating of the specimen. 5 is a set-screw for locking the specimen in the bore. 6 is a handle unitary with the holder. The foregoing structure exemplifies a means for manipulatively holding a cylindrical test-surface specimen.

20 25 7 is a tubular guide for the holder 2. The lower end of the guide is open so as to allow withdrawal of the holder and specimen assembly. A vent hole 12 is provided to conserve ambient pressure within the guide during reciprocation of the holder. This tubular guide is exemplary of means cooperative with the holder to guide the latter as it is caused to be reciprocated.

30 35 40 45 The upper end of the guide is flanged, and is fashioned to form interiorly of that end a chamber 8, having a rigid, non-deformable wall, which chamber serves as a reservoir for the grease-like substance to be deposited on specimen 1. As shown in Figs. 1 through 3, this chamber is in the form of a truncated cone so as to provide internally a central aperture 9 which is coaxial with holder 2; the diameter of that aperture being larger than the diameter of specimen 1, depending upon the thickness of the coating to be applied, but being smaller than the diameter of holder 2. A flanged, internally threaded adapter 10 is mated with the flange of the guide 7 and secured thereto coaxially with respect to chamber 8. An externally threaded cap member or gland 11, centrally apertured for slidably supporting the specimen and cooperative with the adapter, provides, in conjunction with the specimen when the latter is engaged within the member 11 (as shown in Fig. 2), for confinement of the grease-like substance within the chamber under pressure. The foregoing structure exemplifies means associated with the guiding means for housing and confining a grease-like substance under pressure cooperatively with the test-surface specimen.

50 55 60 65 70 The mode of use of our apparatus is as follows:

A cylindrical test-surface specimen 1 is inserted, seated and locked in holder 2 with set-screw 5 (see Figure 4). The holder is then inserted into guide 7 (see Figure 1) and advanced in the guide until the upper extremity of the specimen just enters aperture 9 of chamber 8. The chamber then is filled with the grease-like substance with which it is desired to coat the specimen. Thereupon cap member 11 is threaded partially into the adapter 10 and holder 2 advanced in its guide fully to the position illustrated in Figure 2, in which position the aperture in cap member 11 is completely filled by the specimen. Now the cap 11 is tightened, with small torque so as to exert a pressure on the grease-like substance. Then holder 2 is withdrawn from the guide 7 with an even motion to produce upon the specimen a uniform coating. The specimen may be perforated as at 13 to receive a wire or

the like for facilitating further handling of the specimen without injury to the coating.

We have evaluated the performance of our apparatus according to the following method:

Cylindrical test-surface specimens whose diameters had been measured at various points to the nearest .0001 inch (2.5 microns) for control of specimen uniformity were coated in the apparatus with various greases. The specimens then were cleaned of coating in an arc of surface along their entire length and measured in diameter with a traveling microscope from points upon the uncoated surface across the undisturbed thickness of coating, so as to avoid error through compensating ununiformities of coating at opposite points.

The measurements were made with six different greases on sets of four specimens per grease. The main components of the several greases were varied as follows:

- A—Lithium soap and diester.
- B—Lithium soap and mineral oil.
- C—Diatomaceous earth and diester.
- D—Lithium soap and mineral oil diester blend.
- E—Silica gel and diester.
- F—Sodium soap and mineral oil.

Four points were measured on each specimen at an interval of approximately $\frac{3}{4}$ inch. The same specimens were cleaned, recoated and again measured, this time at three points along each specimen, to evaluate reproducibility. The results are given in the table below, in which the values for the four points of original measurement upon each specimen appear as Determinations Nos. 1, 2, 3 and 4, and the values obtained at three points on each specimen after recoating appear as Determinations Nos. 5, 6 and 7.

For evaluation of effect of certain inherent variables, the data were subjected to an analysis of variance, according to "Statistical Manual, Methods of Making Experimental Inferences" by C. W. Churchman, June 1951. The analysis was directed to:

5 Adequacy of apparatus (tolerances, alignment and concentricity)

Variation in character among greases

Dimensional irregularities in specimens

The data of determinations 1-4 and 5-7 were analyzed separately. The hypothesis used, H_0 , was that the main variables and their interaction had no significant influence on results. The probability of a Type I error —the error of rejecting H_0 when H_0 is actually true—was set at .05. From the analysis—

¹ Measurements along specimens.

² Measurements on different greases.

³ Measurements on different specimens.

The following conclusions may be drawn: The apparatus produces a uniform coating and is capable of reproducing the coating upon several test-surface specimens and with various greases. The thickness of film may vary within a limited range (35-70 microns) among greases differing

in texture and consistency, but uniformity of film is unaffected.

From the foregoing it is evident that we have provided apparatus, adaptive of cylindrical specimens and requiring but ordinary manipulative skill in use, that is capable of producing a uniform coating reproducibly and which consists of a combination of: means for manipulatively holding a cylindrical test-surface specimen; means co-operating with the holding means to guide the latter as it is caused to be reciprocated; and means associated with the guiding means for housing and confining a grease-like substance under pressure cooperatively with the specimen; so that upon completion of a reciprocatory cycle of the holding means, a film of desired character of the grease-like substance is caused to be deposited upon the specimen.

In practicing our invention, the holder and guide must be closely fitted. The bore in the holder, the chamber aperture and the aperture in the cap must be aligned and concentric. In the prototype that yielded the results herein reflected, we utilized specimens varying in diameter from 9.100 mm. to 9.134 mm., and a chamber aperture whose diameter measured $9.233 \pm .002$ mm.

The structure shown and described herein is exemplary and accordingly should be considered illustrative, not 25 limitative.

We claim:

Apparatus for applying to substantially straight, cylindrical specimens a uniformly dimensioned coating of a grease-like substance, such apparatus comprising: a guide 30

having an opening therethrough which opening comprises a conical, first portion and a coaxial, cylindrical second portion having rigid, non-deformable walls, the conical portion serving as a reservoir for the grease-like substance, the conical portion's smaller diameter end being adjacent to the cylindrical portion but being smaller than the diameter of that portion, and the conical portion's smaller diameter end being larger than the diameter of the specimen depending upon the thickness of the coating to be applied; a holder adapted to receive the specimens one at a time, said holder fitting into and being slidable in the cylindrical portion of said guide's opening so that a specimen in said holder is passable coaxially through said guide's conical portion; an internally threaded adapter ring attached to said guide adjacent to and in alignment with that guide's reservoir; and an externally threaded gland in said adapter, said gland being usable to exert pressure on the grease-like substance, the inside of said gland being coaxial with respect to the specimen and being of such size as to slidably accommodate the specimen.
